Philip H. Clark, Willard Webster and Hiram Webster, Trustees
New York —

Letters Patent

The Schedule referred to in these Letters Patent and making part of
the same containing a description in the words of the said Philip
H. Clark, Willard Webster and Hiram Webster themselves of their
invention in the Grist mill.

Be it known that Philip H. Clark, Willard Webster and Hiram
Webster of Truxton County of Oneida and State of New York have made
an improvement in mills, for grinding grain which is described as follows.

The frame is made of four posts formed together by two girts
on each side of the frame. A piece of timber called the bridge tree or
Mill beam is tenoned into or rests on the centre of two of the lower girts.
One of the two girts on which rests the mill beam is moveable to set
the stones for fine or coarse grinding — In addition to the above men-
tioned girts there is one above the moveable girt for the purpose of fasten-
ing the frame together & to receive a bolt running through the moveable
girt and through the before mentioned girt with a nut and screw on
the top for the purpose of raising the mill beam. The size of the timber
varying with the size of the mill, and the height is sufficient to receive
the stones gearing and curb. The hopper and chutes are made in the
usual way. The cap is stationary and rests on the upper girts and
is fastened down by bolts of iron running through the girts on which
it rests with an angle or cleat on the upper end, a nut & screw on the
lower end, or by a bar of iron or wood across the top of the cap and
fastened down to the girts at each end. The cavity in the cap is made
in a conical form to receive the grinding surface of the runner hereafter
described. The runner is a flat surface on the bottom running cap
in a straight line on the sides two inches or more, then the grinding
surface rises in a conical form from one eighth to three eighths of
the diameter of the runner in the centre. The runner & cap are both

made of stone and the medium diameter of the sunnus for grinding grain is about sixteen inches, although not limited. The spindle or shaft running through the centre of the sunnus being fastened to it and of sufficient length below to raise the cap and grinding through and above the cap two inches or more for the purpose of keeping the sunnus in the centre & shaking the stones. said spindle runs in a box pladon or in the mill beam and runs through a box at the top of the cap. or in a box of iron or wood. said box, are both movable to centre the sunnus & plumb the spindle. — This mill may be put in motion by water or any known power by means of a staff and pulley or cog wheel placed in the shaft or spindle. — The mill being put in motion the grain comes at the opening in the cap near the spindle and runs into the sunnus which are turned any direction required and is ground and carried off in the usual way — The invention hereby claimed is the 1. easiness of the construction of the mill. the grinding surface as before described and in dispensing the usual power for grinding.

We testimony that the foregoing is a true description of our invention how we have subscribed our names before two witnesses & made oath to the same this second day of June 1831.

End witness,

Abraham Stark
Edmund Harry,
